VAPOR ELECTRIC DEVICE

Donald E. Henry, Bloomfield, N. J., assignor to
Westinghouse Lamp Company, a corporation of
Pennsylvania

Application August 30, 1933, Serial No. 687,424

4 Claims. (Cl. 176—122)

This invention relates to electric discharge devices and more particularly to devices of this character that exhibit a luminous discharge when in operation. In its more specific aspect the invention is directed to an electric discharge device containing therein an atmosphere of a metal. Although my invention contemplates the employment of sodium, caesium, rubidium, cadmium, zinc or other metal or the like, as at least one component of the gaseous medium in my improved device, I shall hereinafter describe my invention by particular reference to a sodium vapor discharge device.

Prior to my invention it has been proposed to construct a sodium vapor lamp consisting of a plurality of glass containers, with one of said containers having an electron emitting element and sodium therein. The other container was secured to the vapor containing container by fusedly ring sealing one to the other. This operation is difficult to properly perform, especially in those cases where a hermetic air tight seal is desired, and more particularly where the glass is a difficultly workable glass, such as is used in sodium vapor lamps.

As distinguished from the prior art devices I have provided a discharge device including two containers, one within the other, which device may be readily assembled and has improved electrical as well as improved mechanical characteristics.

Briefly, my invention comprises a metal vapor lamp comprising a sealed envelope having an electron emitting means and a metal vapor therein. Another container, which may be evacuated, completely surrounds said envelope which is supported by rigid conductors sealed in said container and said envelope.

An object of my invention is to provide a discharge device of improved mechanical and electrical characteristics.

Another object of my invention is to provide a discharge device that is relatively simple to assemble and is of rugged mechanical construction.

A still further object of my invention is to provide a sodium vapor lamp of simple and novel design, which may be readily manufactured and transported without breakage.

Other objects and advantages of my invention will become readily apparent from the following description and appended drawing wherein,

Figure 1 represents a view in elevation with parts broken away and others in section of an alkali metal discharge device embodying my invention.

Figure 2 represents a fragmentary view in elevation of the supporting means shown in Figure 1.

Figure 3 represents a cross sectional view taken on line III—III of Figure 1.

According to my invention, I provide a vitreous envelope 9 consisting of a sodium vapor resistant glass, such as a special boro-silicate glass. The envelope has the major portion 10 thereof substantially in the form of a sphere having a tubular section or neck 11. Integral with said neck and extending upwardly therein is a reentrant tube having its upper end in the form of a pinch or press 12. Sealed in said press are a plurality of spaced rigid leading-in and supporting conductors 13 and 14 extending exteriorly and interiorly of said envelope.

Rigid conductors 15 and 16 are respectively welded to the conductors 13 and 14. The conductors 15 and 16 extend through insulating plugs 17 located at each end of hollow nickel or other suitable metal cylinders 18 coated with electron emitting material, such as those commonly employed in ultra violet lamps and radio tubes, and consisting of oxides or carbonates of strontium, barium and calcium.

These coated cylinders serve as indirectly heated electrodes and have located therein helical heater filaments, not shown, and whose lower ends are connected respectively to the conductors 15 and 16. The upper ends of these filaments are electrically connected also to conductors 19 and 20 extending through the upper insulating plugs 17. A conductor 21 is electrically connected to the outwardly extending portions of the conductors 19 and 20 so that the heater filaments are in electrical series relationship. Conducting support rods 40 of L shape are welded to the indirectly heated electrode cylinders 18 and to the conductors 15 and 16.

Also located within said envelope is a quantity of an alkali metal such as sodium or the like, and a quantity of rare gas such as neon, argon or helium, or mixtures, at a pressure of about 0.2 mm. of mercury. The gas pressure depends upon the gas used. When argon is employed, I prefer that its pressure shall be about 0.2 mm. of mercury.

In order that the discharge between the electrodes may take place to provide a luminescence for practical lighting purposes, it is necessary that the temperature of the sodium within the envelope be between about 200 and 300 degrees centigrade.

For efficient operation, there is provided an en-

5 closing envelope 22 which completely surrounds the envelope 9 and is composed of a glass that is highly absorbent to infra red rays. The space between the two envelopes is preferably evacuated so that the heat losses from the envelope 9 shall be minimized.

10 So that the discharge device may be rugged and adapted to be transported without breakage and so that it may be readily assembled, the body proper of the envelope 22 is preferably of a generally cylindrical form. It has a re-entrant stem 23 at one end. The stem 23 terminates in a pinch or press 24 of cruciform configuration. Conductors 26, 27, 28 and 29 are sealed in said 15 press, with the conductors being located respectively near the outer ends of the cross arms. Only the conductors 26 and 33 extend both interiorly and exteriorly of said envelope 22.

20 A collar 30 composed of a good heat insulating material, such as asbestos or the like, surrounds the neck 11 of the envelope 10. Tightly wrapped around said collar 30 is a substantially rigid spirally wound spring coil 31 having one end welded to the upper end of conductor 26 and its 25 other end welded to the diametrically opposed conductor 29 for maintaining the envelope 9 in position. The envelope 9 and its associated parts are located in the approximate center of the envelope 22 as shown. In order that bending 30 or excessive vibration of the envelope 9 may be minimized, and so that the complete device may be transported without danger of envelope 9 striking against the envelope 22, I provide short rigid conducting rods 32 welded respectively to 35 the rods 27 and 28 and welded to one or more of the coils of the helical element 31.

36 The rigid leading-in and supporting conductor 13 is welded to the element 31 near one end thereof. Also sealed in said press and located intermediate the conductors 26 and 29 is a rigid conductor 33 extending exteriorly and interiorly of said envelope 22. The conductor 33 is welded at 40 its upper end to that portion of the conductor 14 extending exteriorly of the envelope 9. Thus 45 the leading-in conductors 13 and 14 connected respectively to the leads 26 and 33 serve to support the envelope 9 and its associated parts in proper position. The remaining leads sealed in the press 24 and the rigid spring member 31 also 50 serve to support the envelope 9 and prevents the same from striking the envelope 22.

55 Although my invention has been described with particularity, it is not to be limited by the exact construction described but only by the prior art.

55 What is claimed:

1. An electric discharge device comprising an envelope, a plurality of electrodes therein, said envelope having a press, a plurality of conductors sealed in said press and electrically connected to said electrodes, an envelope surrounding said 5 first mentioned envelope and spaced therefrom, said second mentioned envelope having a cruciform shaped press, a plurality of conductors sealed in said press and electrically connected to said first mentioned conductors for supplying 10 current to said electrodes and means engaging a portion of said first mentioned envelope and having a portion thereof sealed in said cruciform shaped press for maintaining said first mentioned envelope spaced from said second mentioned 15 envelope.

2. An electric discharge device comprising an envelope, a plurality of electrodes therein, said envelope having a press, a plurality of conductors sealed in said press, an envelope surrounding and 20 spaced from said first mentioned envelope, said second mentioned envelope having a press, three supports sealed in said press and supporting said first mentioned envelope, said conductors being so disposed that no more than two of them are in 25 the same vertical plane.

3. An electric discharge device comprising an enclosing envelope, a plurality of electrodes therein, said envelope having a press, a plurality of conductors sealed in said press and extending 30 exteriorly and interiorly thereof, an envelope surrounding and spaced from said first mentioned envelope, said second mentioned envelope having a cruciform press, a plurality of supporting means sealed in said press and circumferentially spaced 35 from each other, said supports maintaining said first mentioned envelope in spaced relation to said second mentioned envelope and supplying current to said electrodes.

4. An electric discharge device comprising an 40 envelope, said envelope having a press, a plurality of conductors sealed in said press and extending exteriorly and interiorly of said press, filamentary heater elements supported by said conductors and being in electrical series relationship, indirectly heated electrodes surrounding said 45 heater elements and also being supported by said conductors, an envelope surrounding said first mentioned envelope, spaced therefrom and having a reentrant stem terminating in a cruciform press, a support located at each half of each cross arm, some of said supports being 50 electrically connected to said conductors.
